UNITED STATES PATENT OFFICE

WILLIAM RAMSAY, OF WASHINGTON, DISTRICT OF COLUMBIA

THERAPEUTIC DEVICE

Application filed June 29, 1928. Serial No. 289,210.

This invention relates to a therapeutic appliance adapted particularly for the application of heat to the human head, along the lines of the bases of the teeth and gums. In carrying out the invention, I provide a heating element comprising a resistance coil of small diameter, wound upon a core and enclosed in a covering of fireproof material, preferably asbestos, the element as a whole being very flexible, and this element is enclosed in a flexible rubber tube which is considerably longer than the coil. Wires extend from the ends of the coil through the tube to a plug switch by which the coil can be connected to a suitable current source. A head-band is provided for holding the device in position, and this band is provided with means at one end for gripping the central part of the tube, and with a gripping device at the other end which is adjustable along the two end portions of the tube. Thus, the tube, with the enclosed heating element, is doubled upon itself, forming two stretches between the gripping devices, and these stretches being flexible and laterally separable, may be positioned along the lines of the bases of the upper and lower gums, in which positions they may be held by the head-band. The stretches of the tube between the gripping or clamping devices are provided with tubular casings of fabric, preferably cotton, which can be readily removed, to be washed, by slipping them along the tube after the removal of the adjustable clamping device.

In the accompanying drawing,

Fig. 1 is a perspective view of the device, showing its application to a human face; and,

Fig. 2 is a front view of the device, partly broken away and partly in section.

The heating device comprises a relatively long flexible resistance coil 1, of small diameter, wound upon an asbestos core 2, the core and coil being enclosed by an asbestos covering 3. This heating element is enclosed within a flexible rubber tube 4, which is considerably longer than the heating element. The ends of the heating element are connected by flexible conductors 5 and 6 to the terminals 7 and 8, respectively, of a detachable plug switch 9, by which the element can be elec-

trically connected, through a socket, to a suitable current source.

The tube and heating element therein are supported by a head-band 10, having at one end a device 11, which grips the central part of the tube 4, and having at its opposite end a gripping device 12, which is adjustable along the end portions of the tube. As shown, these gripping devices are buckle-like in form and they are preferably made of insulating material. The device 11 has openings 13 and 14 and the tube 4 is threaded through these openings, its central part being gripped by the device 11. The gripping device 12 has similar openings 15 and 16, and the end portions 4^a and 4^b of the tube extend through these latter openings. The end portions 4^a and 4^b can be pulled or pushed through the openings in the device 12, to tighten or loosen the device when it is applied to a human head, as shown in Fig. 1.

The stretches of the tube 4 between the gripping devices are provided with tubular cloth coverings 17 and 17^a, preferably of cotton. These coverings can be removed from the tube when desired and replaced by clean coverings.

In applying the device, the gripping device 12 is moved outwardly toward the ends of the tube 4 and the band 10 is slipped over the head, and the part of the device containing the heating element is then arranged opposite the bases of the upper and lower gums, as shown in Fig. 1. By then pulling outwardly on the end portions of the tube 4, the device may be tightened sufficiently to hold the parts containing the heating coil in the position shown. The plug switch 9 may then be connected to the current source, through a suitable socket, and current will flow through the resistance coil. It will be understood, of course, that suitable regulating devices will be provided in the circuit to limit the current flow and produce the desired heating effect in the coil. Preferably, the coil will be raised to such a temperature that the heat applied to the surface of the skin will be fever heat or higher. The application of the heat will stimulate the blood circulation.

What I claim is:

1. A therapeutic device comprising a flexible tube having a flexible resistance coil therein and a head band having devices at its ends for connecting the tube to the band, said tube having two stretches, laterally separable from one another, extending between said devices and connected to the band thereby.
2. A therapeutic device comprising a flexible tube having a flexible resistance coil therein and a head band having devices at its ends for connecting the tube to the band, said tube having two stretches, laterally separable from one another, extending between said devices and connected to the band thereby, one of said devices being adjustable along the stretches.
3. A therapeutic device comprising a flexible tube having a flexible resistance coil therein, a head band having devices at its ends for connecting the tube to the band, said tube having two stretches, laterally separable from one another, extending between said devices and connected to the band thereby, one of said devices being adjustable along the stretches, and removable cloth coverings on said stretches.
4. A therapeutic device comprising a flexible tube, a resistance coil in the tube, a band, means on one end of the band for gripping the central part of the tube, and gripping means at the other end of the band adjustable along the end portions of the tube.
5. A therapeutic device comprising a flexible tube, a resistance coil in the tube, a band, means on one end of the band for gripping the central part of the tube, gripping means at the other end of the band adjustable along the end portions of the tube, and removable cloth coverings on the tube between the two gripping means.
6. A therapeutic device comprising a flexible tube having a flexible resistance coil therein, said tube and coil having sufficient length and flexibility to permit of their extension around the front and sides of the wearer's jaw with light pressure throughout, and a head band having means at its ends connecting the tube to the band.
7. A therapeutic device comprising a flexible tube having a flexible resistance coil therein, said tube and coil having sufficient length and flexibility to permit of their extension around the front and sides of the wearer's jaw with light pressure throughout, and a head band having devices at its ends for connecting the tube to the band, one of said devices being adjustable along the tube.

In testimony whereof I affix my signature.
WILLIAM RAMSAY.

CERTIFICATE OF CORRECTION.

Patent No. 1,747,986.

February 18, 1930.

WILLIAM RAMSAY.

It is hereby certified that error appears in the printed specification of the above numbered patent requiring correction as follows: Page 2, line 30, claim 4, for the word "one" second occurrence, read end; and that the said Letters Patent should be read with this correction therein that the same may conform to the record of the case in the Patent Office.

Signed and sealed this 1st day of February, A. D. 1938.
